UNITED STATES PATENT OFFICE.

WILLIAM C. FIELD, OF DECATUR, ILLINOIS, ASSIGNOR OF THREE-FIFTHS
TO WILLIAM T. DELAHUNTY AND WILLIAM A. SHORB, OF DECATUR,
ILLINOIS.

SAFETY-VALVE.

SPECIFICATION forming part of Letters Patent No. 705,572, dated July 29, 1902.

Application filed March 31, 1902. Serial No. 100,881. (No model.)

To all whom it may concern:

Be it known that I, WILLIAM C. FIELD, of Decatur, in the county of Macon and State of Illinois, have invented certain new and useful Improvements in Safety-Valves, of which the following is a full, clear, and exact description, reference being had to the accompanying drawings, forming a part of this specification, in which similar letters of reference 10 in the different figures indicate like parts.

The object of my invention is to provide a safety-valve for use in connection with gas-pipes and conduits for gas or volatile fluids, such as are commonly used for fuel and illuminating purposes, said valve being so constructed that it will remain open while the temperature surrounding it is normal, but will close and shut off the flow of gas or volatile fluid as soon as the heat becomes excessive, all of which is hereinafter more particularly described, and definitely pointed out in the claims.

In the drawings, Figure 1 is a longitudinal vertical sectional view of a valve embodying 25 the features of my invention, the same being shown as open. Fig. 2 is a like view showing said valve closed; and Fig. 3 is a view of a portion of a building, showing the manner in which said valve may be applied in connection with an ordinary gas-service pipe.

Referring to the drawings, *a* represents the shell of the improved valve, which is provided with internally-threaded nipples *b c* for the reception of induction and eduction pipes. 35 A web having the parts *d e* serves to divide the interior of the valve into two chambers *f g*. A valve-seat *h* is interposed between the parts *d e*, the former of which extends from the lower portion of the shell upwardly and the latter from the upper portion of the shell downwardly to the middle of the chamber, where they unite in said valve-seat, as shown. 40 An annular flange *i* is preferably provided below said valve-seat. A fitting *j* is formed 45 on the top of the shell, into which is tapped a large plug *k*, preferably hollow, having a web *l* in its lower end, which is bored to receive and form a guide for the upwardly-projecting stem *m* of a valve *n*. A spring *o* tends 50 to force said valve upon its seat.

So much of the device as has already been described is old and well known, and I make no claim thereto, except in combination with my improved safety appliance.

Preferably extending upwardly within and from the bottom of the shell is a stud or projection *p*, upon which the enlarged portion *q* of a depending valve-stem is adapted to rest when the valve is closed, the object of which stud will be hereinafter stated. A bore is 55 formed through the bottom of the shell and said projection *p*, which bore is coincident with the axis of the valve *n* and is adapted to receive and serve as a guide for a small stem *r*, which forms the lower valve-stem and extends outside of the casing into a chamber *s*, formed within a hollow nipple *t*, cast upon the lower portion of the shell *a*. Said nipple is exteriorly threaded to receive a cap *u*, open at the bottom, but provided with a flange *v*, 60 between which and the lower end of the nipple is placed a disk *w* of any well-known fusible material or alloy adapted to fuse at a low temperature, the diameter of which disk is smaller than that of the interior of the cap *u*, so as 65 to prevent contact therewith around its edges. Annular washers *x x* of compressed fiber or other non-conducting material are placed, as shown, upon opposite sides of the disk *w* to 70 separate the latter from said metal nipple and cap. A small piece *y* of a like insulating or non-conducting material is interposed between the disk *w* and the lower end of the stem *r*. The object of employing said part *y*, as well as the washers *x x*, and of making the diameter of the disk *w* smaller than that of the cap *v* 75 is to prevent any cooling effect upon the disk as a direct result of metallic contact.

In Fig. 3 I have illustrated the manner in which my improved safety-valve is intended 80 to be applied. In said view *z* represents the outer wall of a building, within which is located the usual gas-meter *z'*. In the service-pipe *z''*, leading from the street to the meter and between said outer wall and the meter, 85 is interposed my improved safety-valve *a*, so that in the event of a fire occurring within the building the heat will cause said valve to close, thereby shutting off the gas from the building.

The operation of my improved valve is as follows: The fusible disk being inserted in position, as shown in Fig. 1, and held in place by means of the cap *u*, the valve *n* is held thereby normally open, so that the gas is free to pass through it in the manner indicated by the arrows in Fig. 1. Should any moisture accumulate within the valve, it will lie around the base of the stud *p*, which prevents it from 5 entering the chamber *s*. Otherwise it might enter said chamber and tend to cool the disk *w* and prevent it from being so readily affected by the heat. In case of a fire the fusible disk *w* melts as soon as the requisite temperature 10 is attained, thereby releasing the valve-stem *r*, which is held upwardly thereby against the action of the spring *o*, and closing the valve.

Having thus described my invention, I claim—

20 1. The combination with a safety-valve, of a spring for closing said valve, a protruding valve-stem, a disk of fusible solder located outside of said valve to serve as a rest for said valve-stem for holding the valve normally open against the action of said spring,

and non-conducting material interposed between said disk and the metal with which it would otherwise be brought into contact, whereby the cooling action of the adjacent metal upon said disk may be obviated, substantially as described. 30

2. The combination with a safety-valve of a spring for closing said valve, a protruding valve-stem, a disk of fusible solder located outside of said valve to serve as a rest for said valve-stem for holding the valve normally open against the action of said spring, rings 35 of non-conducting material located upon opposite sides of said disk to separate the same from its metallic support and non-conducting material interposed between said disk and valve-stem, substantially as and for the purpose specified. 40

In testimony whereof I have signed this specification, in the presence of two subscribers, this 27th day of March, 1902.

WILLIAM C. FIELD.
